UNITED STATES PATENT OFFICE.

ELVIN ASH, OF BERKLEY, VIRGINIA.

BOILER.

1,408,717.

Specification of Letters Patent. Patented Mar. 7, 1922.

Application filed May 11, 1920. Serial No. 380,499.

To all whom it may concern:

Be it known that I, ELVIN ASH, a citizen of the United States, residing at Berkley, in the county of Norfolk and State of Virginia, have invented a new and useful Boiler, 5 of which the following is a specification.

This invention relates to locomotive boilers, one of its objects being to provide a boiler the firebox of which can be readily removed for repairs, the boiler being constructed without the use of bolts and the various walls of the firebox being coupled throughout their length to the shell of the boiler by means of connecting stays.

15 A further object is to provide a boiler in which the crown sheet is so shaped that should the water in the boiler drop to a predetermined level, sealing plugs provided in the sheet will be melted so as to permit water 20 to flow into the firebox and extinguish the fire.

Another object is to provide simple and efficient means for connecting the walls of the firebox and the boiler shell, and for connecting the firebox to the front plate of the boiler.

A still further object is to provide improved means for connecting the boiler tubes to the flue plate.

30 With the foregoing and other objects in view, which will appear as the description proceeds, the invention resides in the combination and arrangement of parts and in the details of construction hereinafter described and claimed, it being understood that, within the scope of what is claimed, changes in the precise embodiment of the invention shown can be made without departing from the spirit of the invention.

40 In the accompanying drawings the preferred form of the invention has been shown.

In said drawings—

Figure 1 is a vertical longitudinal section 45 through a portion of a boiler having the present improvements combined therewith.

Figure 2 is a front elevation of the boiler with the front plate removed.

Figure 3 is an enlarged end elevation of a 50 pair of connecting stays.

Figure 4 is an enlarged face view of a

portion of the flue plate and showing the means for attaching a flue thereto.

Figure 5 is a section on line 5—5, Figure 4.

Figure 6 is a horizontal section through 55 the boiler on line 6—6, Figure 2.

Referring to the figures by characters of reference 1 designates the firebox the crown of which is depressed or concaved transversely as shown at 2 and provided with 60 rounded sides 3. These rounded portions are protected longitudinally by means of guard strips 4 fastened to the side walls 1 and to the crown sheet by rivets or the like and which prevent the flames and heat from 65 coming directly into contact with said rounded portions. At desired points in the crown sheet adjacent the center thereof are plugs 5 of metal which will melt before the crown sheet can burn, these plugs being 70 adapted to melt out should the water reach such a low level as to leave the crown unprotected.

The flue plate 6 at the rear end of the firebox has a series of bosses 7 brazed or otherwise secured thereto, these bosses receiving the front ends of the flues 8. Each of the bosses has recesses extending into the peripheral portion thereof to receive the heads of rivets 10 which are used for fastening 80 the flues to the bosses. By cutting these rivets the flues can obviously be removed readily.

Secured to the sides and top of the firebox are coupling ribs or stays 11 which extend throughout the length of the firebox and are attached thereto by rivets. Each of these ribs has its outstanding flange 12 provided along opposite sides with beads 13 adapted to dove-tail into corresponding 90 grooves 14 formed in the parallel walls of a channeled receiving member 15 riveted to the inner surface of the boiler shell or casting 16. The ribs or stays are of different 95 lengths, those at the sides being shorter than those at the top and the top stays diverging outwardly and upwardly as shown so as properly to support and space the crown 2 of the firebox. The parts are so arranged, however, that the ribs 11 can be inserted longitudinally into the channeled members 15 and when these ribs 11 are riveted to the 100

firebox 1 and the members 15 are riveted to the shell or casing 16, said firebox and casing will be held in proper relation to each other and the various parts of the boiler will 5 be properly braced and supported.

Secured upon the flue sheet or plate 6 are vertically disposed channeled members 17 similar to the members 15 and adapted to be slidably engaged by short rib members 18 10 attached to a plate 19 which is riveted to the bottom of the boiler as indicated at 20.

A flange 21 extends outwardly along the front edge of the boiler casing or shell and is engaged by a channeled extension 21' 15 formed along a flange 22 which extends backwardly from the front plate 23 of the boiler. Rib members 24 similar to the members 18 are secured to and extend vertically upon the front face of the firebox and are 20 slidably engaged by channeled members 25 secured to the inner side of the front plate 23. Braces 26 are arranged obliquely within the front portion of the boiler and are provided with attaching plates 27 riveted to the casing or shell of the boiler and with 25 additional plates 28 riveted to short stays 24' slidably engaged with a short receiving member 25' riveted to the front portion of the boiler.

30 In assembling the parts the firebox is slipped longitudinally into the boiler so that the spacing ribs and channeled members will slide longitudinally into engagement with each other where located along the sides and top of the parts. The plate 19 is then elevated so as to bring the stay member 18 into engagement with the stay member 17 after which said plate is riveted in place as shown at 20. A cotterpin 29 may be inserted through these interfitting members 17 and 18 so as to hold them against relative movement. The front plate 23 is then lowered so as to bring the channeled extension 21' into engagement with the flange at the 45 front end of the shell or casing of the boiler and during this lowering of the front plate the stay members 24 and 25 will move into engagement with each other and can subsequently be fastened by means of a cotter pin 30. The braces 26, which extend downwardly and forwardly from the shell or casing are lowered into the members 25' as shown and, if desired, the interfitting channel 21 and flange therein can be fastened together by rivets as shown.

To remove the firebox it becomes merely necessary to cut the rivets so as to allow the front plate to be lifted out of position. The plate 19 can then be detached and lowered 60 after which the firebox can be moved forwardly out of the boiler, it of course being necessary first to cut the rivets which engage the front ends of the flues 8, these rivets

being easily reached by a tool inserted into the recesses 9.

65

What is claimed is:

1. The combination with a boiler shell and stay members extending longitudinally along the walls and top thereof, of a firebox insertible longitudinally into the shell, stay members thereon at the top and sides thereof and insertible into engagement with the stay members on the shell during the insertion of the firebox into the shell, a front plate movable across the front end of the shell, and into engagement therewith, and stay members upon the firebox and front plate movable into engagement with each other during such positioning of the front plate to tie the front plate to the firebox. 70 75 80

2. In a boiler the combination with a shell having an outstanding flange at one end, and longitudinal stay members upon the top and walls of the shell, of a firebox insertible longitudinally into the shell, stay members thereon movable into engagement with the stay members on the shell during the insertion of the firebox to tie the firebox and shell together, a front plate movable to position across the open end of the shell and 90 into engagement with the flange thereon, and cooperating stay members upon the front end of the firebox and upon the shell for engagement with each other during the positioning of the front plate to tie the front 95 plate to the firebox.

3. In a boiler the combination with a shell having longitudinal stay members, of a firebox insertible longitudinally into the shell and having a flue plate, stay members upon the flue plate, stay members upon the sides and top of the firebox and insertible into engagement with the stay members in the shell during the insertion of the firebox, to tie the firebox and the shell together, a plate 100 attachable to the boiler, stay members carried thereby and movable into engagement with the stay members on the flue plate, a front plate movable to position across one end of the shell and into engagement with 105 said shell, stay members upon the front of the firebox and upon the front plate, said members being movable into engagement with each other during the placing of the front plate to tie said plate to the firebox, 110 and braces diagonally disposed within the shell and attached to the shell and front plate.

In testimony that I claim the foregoing as my own, I have hereto affixed my signature in the presence of two witnesses.

120
ELVIN ASH.
